(57)

CLAIM

The ornamental design for a mule as shown and described.

DESCRIPTION

FIG. 1 is a bottom view of the mule showing our new design; FIG. 2 is a top view thereof;

FIG. 3 is a right side view thereof;

FIG. 4 is a back view thereof;

FIG. 5 is a perspective view thereof;

FIG. 6 is a left side view thereof;

FIG. 7 is a front view thereof;

FIG. 8 is a bottom view of an alternative embodiment;

FIG. 9 is a back view thereof;

FIG. 10 is a perspective view thereof;

FIG. 11 is a left side view thereof;

FIG. 12 is a right side view thereof;

FIG. 13 is a top view thereof; and,

FIG. 14 is a front view thereof.

The broken lines showing the interior of the mule and the sole of the mule are not claimed as part of the design.

1 Claim, 14 Drawing Sheets
